UNITED STATES PATENT OFFICE.

CHARLES D. SEEBERGER, OF NEW YORK, N. Y.

SIGNAL DEVICE FOR ELEVATOR SYSTEMS.

1,223,527.

Specification of Letters Patent.

Patented Apr. 24, 1917.

Original application filed August 1, 1907, Serial No. 386,665. Renewed October 24, 1912, Serial No. 727,623.
Divided and this application filed March 13, 1914. Serial No. 824,356.

To all whom it may concern:

Be it known that I, CHARLES D. SEEBERGER, a citizen of the United States, residing at New York, in the county of New York and State of New York, have invented certain new and useful Improvements in Signal Devices for Elevator Systems, of which the following is a specification, reference being had therein to the accompanying drawing.

10 This invention relates to signal devices for elevator systems in which adjacent cars are independently actuated and controlled both up and down in the same shaft, and consists in the matters hereinafter described and 15 then pointed out in the appended claims.

In the accompanying drawings which show embodiments of the various features of my present invention,

Figure 1 is a side elevation of an indicator or tell-tale mounted in each of the cars;

Fig. 2 is a front elevation of the same with the wirings for the circuits;

Fig. 3 is a front elevation of one form of 25 controlling device in the cars showing the same connected in the electrical circuits of the indicator of Fig. 2;

Fig. 4 is a side view partly in elevation and partly in section of the controlling device of Fig. 3;

Figs. 5 and 6 are side and front views showing two adjacent cars and their associated devices for actuating the tell-tale or indicator;

Fig. 7 is a detail view partly in section and partly in elevation showing the indicator devices of Fig. 2 utilized for shifting the operating device of the car, and also showing certain electric features;

Fig. 8 is a view showing an end elevation of parts of Fig. 7 and also showing certain other parts in section and in elevation;

Fig. 9 is a plan view of certain parts shown in Fig. 8;

Fig. 10 is a plan view of the solenoid of Fig. 8 with its safety catch; and

Fig. 11 is a diagrammatic view showing a series of signals in one car and the electrical circuits therefor extended in position to 50 illustrate their connection with associated devices in another car.

In utilizing the various features of my invention any number of cars may be employed, depending on the length of the run.

or height of the shaft, and for purposes of 55 illustration two cars 31 and 32 are shown with the understanding that the various features may be employed for a larger number of cars by extending or duplicating the several devices or appliances. The cars here 60 shown operate in the same shaft, and each normally moves independently of the others, being operated by suitable cables (not shown) and running on suitable guides, such for example as shown at 44, the construction and operation of these and other 65 associated parts and devices being preferably as shown in my application originally filed August 1st, 1907, bearing Serial Number 386,665, renewed October 24, 1912; re- 70 newal Serial Number 727,623, of which the present application is a division and continuation.

An important feature of my invention resides in an indicator or tell-tale showing in 75 any car the proximity of an adjacent car, and which may be employed in any location where cars travel on the same run or track or in the same shaft. The details of this feature may be varied but in the preferred 80 form I provide a tell-tale which will show in any car the proximity of an adjacent car by scale, by lights, by sound and by the feeling or touch of the operator. Referring more especially to Figs. 1 and 6, each car is 85 provided with a short shaft 84 projecting through one of the walls thereof and provided at its inner end with a worm gear 85 and at its outer end with the drum 86. The drums of adjacent cars are connected by a 90 distance cable or rope 87 which is wrapped around the drums so as to revolve them when it is moved, and provided at its ends with weights 88. It is obvious that as the 95 space between the cars diminishes, the weights will descend, thus operating the associated drums. Each car is provided adjacent the gear 85 with a suitable bracket 89 in which a spiral gear 90 is revolvably mounted. The gear 90 meshes with the gear 85, 100 and is provided with a central threaded aperture which is in threaded engagement with the correspondingly threaded shaft 91, the gear 90 serving as an actuator to revolve the shaft in such direction and at such speed 105 that the shaft always is positioned in the gear corresponding to the distance between adjacent cars. The bracket 89 is suitably

provided with projecting sleeves 92 to provide suitable bearing surface and support for the shaft 91, which at its upper end carries a suitable frame 93 slidably mounted upon guides 94 attached to the inner wall of the car. The sliding-frame is provided with transparent portions of different colors, such as panels 95, 96 and 97 of white, green and red glass respectively, preferably alternating with opaque portions of the frame. A suitable light 98 is attached to the car in the rear of the frame, so that as the frame slides up and down upon its guides the light will illuminate the different transparent portions of the frame. The car is also provided with an indicator in the nature of a pointer 99 operating in conjunction with a scale upon the sliding frame to show the distance apart of adjacent cars in convenient units, preferably by units indicating the numbers of the floors or landings, thus also indicating the number of floors intervening between the elevator cars.

Each car is also provided with a buzzer or an alarm bell 10 which is in a normally open circuit including a pair of opposite contacts 101 and 102 and a battery 103. This circuit also includes a branch to a pair of contact plates 104 carried by the car adjacent the controlling-lever 105 which actuates a suitable device 106 controlling the running or operating ropes 107 extending to the source of power to start and stop the car, the arrangement being such that the lever bridges the space between the plates 104 to provide electrical continuity therebetween for a purpose to be herein-after described, the contacts 101 and 102 being carried by the car in such position as to be closed by a brush 108 attached to the sliding-frame 93 when the latter moves downwardly. Each car is also provided with a second bell or gong 109 which is in a normally open circuit including the opposite contacts 101 and 110 and the batteries 103 and 111, the contact 110 being placed below the contact 102 and in position to be closed with the contact 101 by the brush 108 when the sliding-frame travels toward its lowest point, it being obvious that when the circuit is closed between the contacts 101 and 110, the gong 109 is operated with double battery power. The circuits of the alarm bells and their associated parts are shown in Fig. 2, and it is obvious that they may be arranged in any suitable manner; preferably they include the contact-plates 104 for the purpose of operating a suitable vibrator in the handle of the controlling lever 105. To this end the handle of the lever is made hollow to receive a suitable magneto vibrator 112, operated by the armatures of a pair of magnets 113. This magneto-vibrator is inclosed in a suitable casing mounted upon the handle, and is

provided with suitable wiping contacts 114 to coöperate with the contacts 104 and suitably connected to the wires of the magnets.

When the system is installed adjacent cars are arranged at a predetermined distance apart with their respective indicator frames set in the position shown in Fig. 2, and the drums 86 are connected with a stretch of rope equal to such predetermined distance; in the present instance this distance is assumed to be equal to the space of six stories or floors of an associated building, for convenience of illustration, it being of course obvious that it may be varied. When the distance between the cars diminishes, the weights descend and operate the drums and indicator frames which then descend on their guides. The parts are so related that the normal position of the frames preferably will be such as to show the light 98 through the white glass or panel 95, and to have the indicator point to any number on the scale indicating a predetermined distance apart of two cars, as here six stories. When now the cars approach to lessen this distance, the stretch of the running rope between their drums slackens to allow the weights to descend from their drums to revolve the latter to turn the gears 90 whose revolutions move the threaded shafts 91 in such direction and at such speed that this fact is indicated in each car by its pointer 99 and light 98 which show the scale and glass panels respectively the relative distances between cars. When the distance between the cars is reduced, to say three stories, the green panel is illuminated and the buzzer 100 and vibrator 112 are operated; when the distance is further reduced the red panel is illuminated and gong 109 sounded in addition to operating the vibrator; by this means the warning effect or signal indicia is increased as the distance between the cars within the predetermined zone increases. Each operator is thereby informed of the relative distance between his car and adjacent cars at all times, and as the cars approach nearer than the predetermined distance signals to the senses of sight, hearing and touch of the operator are simultaneously operated. When the distance between the cars increases the stretch of the running rope between them is drawn taut and the drums are revolved by the rope to move the frames toward their initial positions which they reach when the cars reach the predetermined distance apart. While the drawings illustrate the parts as applied to only two cars, it is obvious that the application to a greater number of cars would be clearly within the scope of the present invention.

Any one of the several signal devices just described, which are the same upon and in connection with each car, may be used

alone, or for the sake of securing greater effectiveness of operation two or more, or all, may be employed in coöperation.

While the operation of the indicator suffices to govern the movements of the cars, I have devised certain further mechanisms which may be used in supplement thereto for mechanically or automatically controlling the cars.

10 One of these devices is a speed-governor, which is adapted for use upon cars operating in separate shafts but is especially useful in systems where a plurality of cars operate in the same shaft. This feature is illustrated 15 in Figs. 3 and 4, in which the controlling device 106 coöperating with the running or shifting ropes 107 controlling the source of power is provided with an arm 115 adapted to contact with a guide 116, an anti-friction 20 wheel 117 preferably being provided in the end of the arm. The guide is placed in the lower part of the shaft, and the arm is attached to the shifting device of a relatively upper car, as car 31 for example in the present showing, and the arrangement is such 25 that the guide holds the shifting device against movement in the direction to increase the speed of the car. By this means the speed of the car is automatically reduced, and when an upper or express car 30 traverses that part of the shaft used by a lower or local car, the speed of the express car may not exceed that of the local car. The parts may be set to make the maximum 35 speed of the express car equal to or less than the speed of the local car.

Another feature of my invention consists in providing means to automatically shift the operating device of the car when it approaches within a predetermined distance of the next car, whereby either or both cars shall be automatically slowed up or stopped until the normal distance between them is again established. For this purpose I utilize a distancing-device, such as the weighted cable and its drums, which at any predetermined point shifts the operating device of a car to either slow up or stop the car as may be desired. Referring to Fig. 7 it will be seen that the shaft 91 of the indicator is extended through the floor of the car and is provided with a rack 118 operating a pinion 119 upon a bar 120. The pinion is provided with a central threaded sleeve or aperture 45 adapted to engage a thread upon the bar, and is held against displacement by stops 121, the several parts being mounted upon the lower portion of the frame of the car in any suitable manner. The bar is provided 50 with a yoke 122 engaging a pin 123 in the usual controlling device 106 on the lever 105 and which operates the shifting ropes 107 controlling the operating or power device. When the distance between an upper and a 55 lower car is reduced to a predetermined

point the action of the distancing cable 87, as above described, causes the rack to revolve the pinion 119, the revolution of which moves the threaded shaft in such direction and at such speed that the yoke shifts the part 106 to either slow up or stop either or both cars. The ropes 107 are so arranged on the shifting device that the levers of the upper and lower cars are at the same angle when the car directions are opposite. The 70 device may operate to check or stop both cars when they are moving in opposite directions or in the same direction either up or down; it will check or stop the cars according to the extent it moves the controlling device 106 toward the latter's "stop" position, which of course is determined by the movement transmitted by the distancing device. It is also obvious that the extent of movement thus transmitted to the controlling device may be such as to reverse the direction of travel of the car by moving the controlling device 106 past its "stop" position. The shifting device may be on all cars running in the same shaft, or it may be applied only on the upper car or cars. 85

Another feature consists in providing mechanism which gradually increases the friction of a car-grip upon the guides as the predetermined distance between the cars is 90 reduced and until the grip stops the car when this distance has been reduced to its minimum of safety. For this purpose the hub of the pinion 119 is provided with a sprocket 124 having a chain 125 running over a sprocket 126 on a brass sleeve 127 of a solenoid mounted on the lower portion of the frame of the car. The wires of the solenoid are arranged in a band 128, their ends being mechanically connected to the 100 sleeve 127 and electrically connected to a metallic arbor or roller 129, as shown in Fig. 8, which is revolvably mounted on the frame and is provided with suitable means, such as a weighted rope 130, to wind the 105 wires thereon. The wires are secured to the sleeve 127 by means of a common conductor 131, which is in electrical connection with a metallic disk 132 contacting with a brush 133 from which the wire 134 leads to one 110 side of a suitable battery or other source of electrical supply. The arbor 129 is electrically connected by conductor 135 to the other side of the battery. The core 136 of the solenoid is provided with an extension 115 137 operating a toggle joint 138 whose arms are connected to the pivoted arms of a suitable friction grip 139 engaging one of the guides, as 44, fixed in the elevator shaft. This friction device is operated by a suitable 120 distancing-device, such as the weighted rope 87, coöperating with any suitable intermediate transmitting mechanism as the shaft 91 and pinion 119. When the distancing device acts, as above described, the shaft 91 is 125 130

lowered and the sprocket chain 125 causes the sleeve 127 to revolve in the direction of the arrow in Fig. 8 against the force of the weight and to wind the wires on the sleeve 5 to build up the solenoid. This building-up of the solenoid causes the core to be drawn within the sleeve to operate the toggle and gradually increase the friction of the grip on the guide until finally the grip holds 10 fast on the guide when the cars have approached to the minimum distance apart. The grips shown comprise a pair of pivoted jaws whose arms are connected to the arms of the toggle, but they may be of any 15 suitable form.

A suitable indicator to acquaint the operator of a car with the direction of travel of an adjacent car or cars may be employed, and for this purpose I employ the devices 20 shown in Figs. 7 and 11, in which the adjacent wires are to be considered as connected. A cable 162 containing electrical conducting wires extends between the cars 31 and 32 respectively, its conductors connecting suitable signals in one car with circuit contacts 25 in another car adapted to be closed at different positions of the controlling lever of an adjacent car. One of the cars carries a signal such as a lamp 163 suitably connected by wires in the cable to a pair of contacts 164 and 165 arranged adjacent to a portion of the path of travel of the lever in an adjacent car, the contact 165 being preferably divided and connected by a suitable resistance 166 for a purpose hereinafter 30 described. This local circuit is provided with a battery, and the lever of the second car is adapted to close the circuit between the contacts 164 and 165 when thrown from its central or inoperative position to any 35 point in the corresponding direction of the contacts, thereby lighting the lamp 163 in the first car. A companion lamp 167 is provided in the first car similarly connected in a circuit including the battery with corresponding contacts 164 and 168 in the second car, adapted to be bridged when the operating lever is thrown to reverse the direction of travel of its car. The contact 168 is 40 likewise divided into a series of separate contacts connected by a suitable resistance 169. By this means lamp 163 is lighted when the second car moves down, and the lamp 167 is lighted when the second car moves up, thus indicating to the operator of each car the direction of travel of the other car.

This direction signal may include the resistances as above described for the additional function or purpose of furnishing a speed indicator in connection with the direction indicator, as it is obvious that the resistances connecting the series of contacts 165 and 168 respectively add brilliancy to 45 the lamps in the first car as the speed of the

second car increases. Similar arrangements may be provided from the first to the second car to indicate to the operator of the second car the direction and speed of movement or travel of the first.

The cable 162 may have suitable wires connecting telephones 170 in adjacent cars and comprising suitable equipment for telephonic communication between the cars.

Although I have shown and described 75 constructions and arrangements for carrying out the various features of my invention, I do not limit the invention to such particular forms.

I claim:

1. In an elevator system, a pair of cars adapted to independently move in the same shaft; a distance device connecting the cars; and a signal device in one of the cars operated by the distance device when the cars 85 approach within a predetermined distance.

2. In an elevator system, a pair of cars adapted to independently move in the same shaft; a distance device connecting the cars; and a signal device in each car operated by 90 the distance device when the cars approach within a predetermined distance.

3. In an elevator system, a pair of cars adapted to independently move in the same shaft; a distance device connecting the cars; 95 and signaling means in one of the cars having increasing warning indicia operated by the distance device when the distance between the cars decreases within a predetermined zone.

4. In an elevator system, a pair of cars adapted to independently move in the same shaft; a distance device connecting the cars; and signaling means in each car having increasing warning indicia operated by the 105 distance device when the distance between the cars decreases within a predetermined zone.

5. In an elevator system, a pair of cars adapted to independently move in the same 110 shaft; a distance device connecting the cars; a plurality of signals in one of the cars; and means in said car operated by the distance device to successively operate the signals 115 when the distance between the cars decreases within a predetermined zone.

6. In an elevator system, a pair of cars adapted to independently move in the same shaft; a distance device connecting the cars; a plurality of signals in each car; and means 120 in each car operated by the distance device to successively operate its signals when the distance between the cars decreases within a predetermined zone.

7. In an elevator system, a pair of cars 125 adapted to independently move in the same shaft; a distance device connecting the cars; and an indicator in one car operated by the distance device to show different predetermined distances between the cars.

8. In an elevator system, a pair of cars adapted to independently move in the same shaft; a distance device connecting the cars; and indicating means in one car operated by the said device to show different predetermined distances between the cars, and comprising visual and aural signals. 5
9. In an elevator system, a pair of cars adapted to independently move in the same shaft; a distance device connecting the cars; and indicating means in one car operated by the said device to show different predetermined distances between the cars, and comprising signals for the sight, hearing and touch of the operator. 10
10. In an elevator system, a pair of cars adapted to independently move in the same shaft; a distance device connecting the cars; and an indicator in one car operated by the said device to show different predetermined distances between the cars, and comprising a moving and a stationary member. 15
11. In an elevator system, a pair of cars adapted to independently move in the same shaft; a distance device connecting the cars; aural-signal circuits and an indicator in one car operated by the said device to show different predetermined distances between the cars, and comprising a moving frame having visual indicating devices and means to close the aural-signal circuits. 20
12. In an elevator system, a pair of cars adapted to independently move in the same shaft; handles to control the operation of the cars; vibrators in the handles; a distance device connecting the cars; and means operated by the distance device to operate the vibrators when the cars approach nearer than a predetermined distance. 25
13. In an elevator system, a pair of cars adapted to independently move in the same shaft; handles to control the operations of the cars; electrical vibrators in the handles; a distance device connecting the cars; a circuit including said vibrators and a suitable source of electrical power; and an indicator in each car operated by the distance device and closing the circuit when the cars approach within a predetermined distance. 30
14. In an elevator system, a pair of cars adapted to independently operate in the same shaft; a distance device connecting the cars and comprising a drum on each car and a cable to revolve the drums as the distance between the cars is reduced; and an indicator in one of the cars operated by the drum thereof when said car approaches within a predetermined distance of the other car. 35
15. In an elevator system, a pair of cars adapted to independently operate in the same shaft; a drum on each car; a cable to revolve the drums as the cars approach nearer than a predetermined distance; a gear on each car operated by its drum; a shaft on each car moved longitudinally by the rota- 40
- tion of its gear; and a signal device in each car operated by the shaft. 45
16. In an elevator system, a pair of cars adapted to independently move in the same shaft; a distance device connecting the cars comprising a cable and drums on the cars revolved by the cable as the distance between the cars is reduced; a gear on each car operated by its drum; a shaft on each car moved longitudinally by the rotation of its gear; and an indicator in each car controlled by its shaft to indicate when it approaches within a predetermined distance of the other car. 50
17. In an elevator system, a pair of cars adapted to independently operate in the same shaft; a distance device connecting the cars and comprising a drum on each car and a cable wound on the drums and having its ends weighted; and an indicator operated in one of the cars by the drum. 55
18. In an elevator system, a pair of cars adapted to independently operate in the same shaft; a drum on each car; a cable wound on the drums and having its ends weighted; and a signal device in each car operated by its drum. 60
19. In an elevator system, a pair of cars adapted to independently move in the same shaft; a distance device connecting the cars comprising a drum on each car and a cable wound on the drums and having its ends weighted; and means in each car controlled by its drum to indicate different predetermined distances between the cars. 65
20. In an elevator system, a pair of cars adapted to travel independently in a common shaft; a signal device in each car; a cable movably connected with the cars; and connections between the cable and signal devices to operate the latter when the cars approach nearer than a predetermined distance. 70
21. In an elevator system, a pair of cars independently movable in the same shaft; a signal device in each car; a cable movably connected with the cars; and means operated by the cable to operate the signal device of an approaching car at a predetermined length of the cable. 75
22. In an elevator system, the combination with two cars independently movable both up and down in the same shaft; of a cable movably connected with the cars, and a signal device in each car operated by the cable when the cars approach within a predetermined distance. 80
23. In an elevator system, the combination with two cars independently movable both up and down in the same shaft; of a drum on each car, a cable wound upon the drums, and signal mechanism in each car operated by the cable when the cars approach within a predetermined distance. 85
24. In an elevator system, the combination 90
- 95
- 100
- 105
- 110
- 115
- 120
- 125
- 130

of two cars independently movable both up and down in the same shaft; signal mechanism in each car; a drum on each car controlling its signal mechanism; and a cable wound on the drums to operate them when the cars approach within a predetermined distance.

In testimony whereof I affix my signature in presence of two witnesses.
